UNITED STATES PATENT OFFICE.

JOHN E. DOLDT, OF PORTLAND, MAINE, ASSIGNOR TO NATIONAL METAL SEAL CORPORATION, OF BOSTON, MASSACHUSETTS, A CORPORATION OF MAINE.

CLOSURE FOR CONTAINING VESSELS

1,153,897.

Specification of Letters Patent. Patented Sept. 21, 1915.

Application filed May 28, 1913. Serial No. 770,323.

To all whom it may concern:

Be it known that I, JOHN E. DOLDT, a citizen of the United States, residing at Portland, county of Cumberland, State of Maine, have invented certain new and useful Improvements in Closures for Containing Vessels, of which the following is a specification.

This invention relates to closures for containing vessels and particularly to closures for that class of receptacles which are subject to frequent opening, and which must be tightly sealed when closed.

The present invention contemplates a container having a series of spaced lugs about its mouth and a closure having a depending skirt provided with inturned spring lips adapted for engagement with said lugs by rotation of the closure. The lips of the cap 20 are considerably longer than the lugs of the container and are undeturned substantially horizontally and meet the cap skirt at substantially a right angle. The lips therefore serve as trusses to brace the cap rim against serious buckling or distortion as the cap is tightened and assist to draw the cap downwardly and inwardly on to the container. This affords a lug engaging surface which is inherently resilient to permit the lips to 30 yield in passing over the lugs while possessing sufficient rigidity to prevent permanent distortion of the cap skirt.

The structure and principle of the closure will be more fully set forth in the specification which follows, and in the drawings which form a part of that specification, I have shown an embodiment which has been found well adapted to practical use and the requirements of manufacture.

Throughout specification and drawings like numerals of reference indicate corresponding parts, and in the drawings: Figure 1 is a side elevation of a container with a closure in accordance with my invention applied thereto, the cap being shown in section, Fig. 2 is a plan view thereof, Fig. 3 is a bottom plan view of the cap with the relative positions of a lug indicated in dotted lines. Fig. 4 is a partial plan view of one of the container lugs on an exaggerated scale with dotted lines diagrammatically illustrating the positions of the edge of the lip of the cap as in Fig. 3, Fig. 5 is a side elevation on an exaggerated scale of one of the container lugs with the planes of engage-

ment by the cap lip indicated, and Fig. 6 is a vertical central section of a lug with dotted vertical contour lines and the positions of the cap lip indicated.

For the purpose of adequately disclosing my invention I have been compelled to deal with it largely from a diagrammatic standpoint, and the various figures of the drawings are of necessity exaggerated to show the relative phases of engagement of the cap with the container.

I have indicated at 1 a container which may be of any desired size, form or material having a shoulder 2 about its mouth. In practice, this container is usually made of opal or flint glass, and it is to this class of containers that my closure is particularly adapted. About the shoulder of the container I form a plurality of spaced lugs 3, the specific form of which will be more fully disclosed hereinafter.

The closure for the container consists of a cap 4 provided with a pack 5. The cap is formed about its periphery with a depending flange or skirt 6, which has spaced about its edge a plurality of inturned lips 8 with their inner edges extending across in substantially the line of a chord. These lips 8 are spaced so as to leave gaps 7 of sufficient size to permit the passage of the lugs 3. The portion of the flange included between said gaps 7 form segmental lips 8 which, during the rotation of the cap, move in and under the lugs 3 and effect an exceedingly secure engagement of the cap on the container. The cap being made of metal has a certain amount of flexibility and increases the cam engagement as will be seen by reference to Figs. 5 and 6, in which the upward and horizontal curvature of the lugs appear. The upward curve starts from the center of the front face of the lug and gradually slopes down to each side. This forms a double cam having its point of greatest height at the center of the lug and its respective cam faces 9 pitched in opposite directions therefrom and of gradually decreasing thickness as they approach the ends of the lug. The lips of the cap may therefore pass up or down either upward cam face of the lug, the engagement becoming tighter and tighter as the lip approaches the center of the lug. This means that the cap may be seated and unseated by the partial rotation in either direction. The horizontal curving

of the under face of the lug 3 as indicated at 10 gives a second cam action radial in its line of direction and effective to cause the lips of the cap to ride in under the faces of 5 the lug and reach their point of tightest engagement at the center of the lugs, which point is, as will be remembered, the maximum height of the cam. I therefore round off each corner of the lug as indicated by 10 the reference numeral 10. It is with these rounded corners that the cap lips first engage when being applied to the lugs. The under face of the lug is also slightly beveled upwardly from rear to front, which inclined 15 face provides a cam surface 11. As the cap lip approaches the center of the lug it is gradually working under said inclined face 11 and the engagement is becoming tighter and tighter reaching its maximum degree of 20 tightness at the center of the lug. This action I have attempted to illustrate diagrammatically in Figs. 3 to 6 inclusive. In these figures I have shown several of the infinite number of phases of movement of one of 25 the lips 8 in engaging a lug. The diagrams are of necessity exaggerated to bring out the action clearly.

In applying the cap to the container the gaps or slots 7 are first brought in line with 30 the lugs of the container. The cap is then pressed down over the lugs and may be turned in either direction. At the beginning of this rotation the adjacent bearing edge of each lip is in the position indicated by 35 dotted lines *a* in Figs. 4, 5 and 6, and just clears the lug. As the cap is turned the lip gradually engages one of the cam faces 9 of the lug and at the same time it is bearing in under one of the rounded shoulders 40 10 of the lug and making its way in along the beveled under face 11 thereof. This position of the lip relative to the lug is indicated by the dotted line *b* and may be termed the intermediate phase of movement, 45 although this expression is not strictly speaking true, since the movement is a gradual and varying one and is really composed of an infinite number of imperceptible phases. The idea to be conveyed, however, 50 is that the lip has begun to be forced in under the cam face 11 of the lug and is gradually approaching the shoulder 2 of the container. The continued rotation of the cap brings the lip into the position indicated by 55 the dotted lines *c*. Here the lip is represented as having reached the maximum height of the lug and the maximum degree of tightness of engagement of lip and lug has been attained. In other words, the center 60 of the lip has reached the center of the upward cam face of the lug and the finger has been forced in along the inclined under face 11 of the lug as near to the shoulder of the container as it can go. In this position 65 the cap is locked against anything but

an intentional rotation to unseat it. This displacement may be either a continued forward turn of the cap or it may be a reverse turn, the effect in either instance being to disengage the lips from their camming engagement with the lugs. 70

By forming the inturned ends of the lips 8 on the line of a chord, the lips serve as trusses to brace the cap rim against serious buckling or distortion as the cap is tightened. 75 This form of lip provides a lug engaging surface which is inherently resilient but none the less possesses considerable rigidity, that is to say, while the lip is sufficiently resilient to permit it to pass over the cam surfaces of the lugs, at the same time it is so disposed as to brace the cap rim against buckling. Where the engaging member has been a simple hooked finger, both it and the cap rim have been liable to permanent distortion because there was not present sufficient rigidity to resist the stress produced in setting the cap. The lips 8 of the present device are considerably longer than the lugs and being disposed on the 80 lines of chords not only brace the cap rim as a truss, but serve to draw the cap downwardly and inwardly on the container. 85

Various modifications in the form and disposition of the parts may obviously be made 90 and the lips and lugs reversed from cap to container, all without departing from the spirit of my invention if within the limits of the appended claims.

What I therefore claim and desire to secure by Letters Patent is:

1. In combination with a container having relatively short spaced lugs about its mouth each lug having an upwardly beveled lower face and having lateral cam surfaces sloped toward each other from opposite ends of the lug, a closure for said container having relatively long resilient lips disposed for progressive engagement with said lateral cam surfaces of the lugs, said lips terminating in an inwardly directed edge disposed for engagement with the under faces of said lugs whereby to draw said closure downwardly and inwardly on to the container. 105 110

2. In combination with a container having spaced lugs about its mouth, each lug having an upwardly beveled lower face and having lateral cam surfaces sloped toward each other from opposite ends of the lugs, a closure for said container having depending resilient lips disposed for progressive engagement with said lateral cam surfaces of the lugs, said lips terminating in an inwardly directed edge disposed for engagement with the under faces of said lugs and said inner edges disposed substantially in the line of a chord whereby to draw the closure downwardly and inwardly on to the container as it is tightened. 115 120 125 130

3. In combination with a container having relatively short spaced lugs about its mouth, each lug having an under bearing surface and a lateral engaging portion rounded both upwardly and laterally, a closure for said container comprising a cap having a depending skirt, and relatively long resilient lips extending inwardly from said skirt, the inner edges of said lips meeting and forming a juncture with the edge of the skirt.
4. In combination with a container having relatively short spaced lugs about its mouth, each lug having an under bearing face and having a lateral engaging face, a closure for said container comprising a cap having a depending skirt, and relatively long inwardly directed resilient lips on said skirt, each lip substantially in the form of a segment and connected to said skirt at its ends in truss relation thereto.
5. In combination with a container having relatively short spaced lugs about its mouth, each lug having an under bearing

face and having a lateral engaging portion, 25 a closure for said container having relatively long resilient lips disposed for progressive engagement with said lateral faces of the lugs, said lips each terminating in an inwardly directed edge disposed for engagement with the under faces of said lugs whereby to draw said closure downwardly and inwardly on to the container.

6. In combination with a container having relatively short spaced lugs about its 35 mouth, each lug having an under bearing face and having a lateral engaging face, a closure for said container comprising a cap having a depending skirt, relatively long inwardly directed resilient lips on said skirt 40 connected to said skirt at their ends in subtending truss relation thereto.

In testimony whereof I affix my signature in presence of two witnesses.

JOHN E. DOLDT.
